Primary Examiner — Sandra Snapp(74) *Attorney, Agent, or Firm* — Clark & Brody(57) **CLAIM**

The ornamental design for a massage tool applicator holder, as shown and described.

DESCRIPTION

FIG. 1 is a right side elevation view of a massage tool applicator holder showing my new design.

FIG. 2 is a top plan view thereof.

FIG. 3 is a front elevation view thereof.

FIG. 4 is a rear elevation view thereof.

FIG. 5 is a left side elevation view thereof.

FIG. 6 is a bottom view thereof; and,

FIG. 7 is a left side elevation view thereof showing the environment in phantom lines.

The broken lines shown in the drawings are for illustrative purposes only and form no part of the claimed design.
